UNITED STATES PATENT OFFICE.

CARL ALRIK HULT AND OSCAR WALFRID HULT, OF STOCKHOLM,
SWEDEN.

ROTARY ENGINE.

SPECIFICATION forming part of Letters Patent No. 787,762, dated April 18, 1905.

Application filed September 22, 1904. Serial No. 225,522.

To all whom it may concern:

Be it known that we, CARL ALRIK HULT and OSCAR WALFRID HULT, subjects of the King of Sweden and Norway, and residents of Inedalsgatan 1, Stockholm, in the Kingdom of Sweden, have invented certain new and useful Improvements in Rotary Engines, Pumps, and the Like, of which the following is a specification, reference being had therein to the accompanying drawings.

This invention relates to rotary engines, pumps, or the like of that class in which the casing or cylinder for reducing the friction between the same and the piston drum or roller mounted eccentric in the said casing and rotating in contact with the inner surface of the same is made rotatable, so that it is caused to rotate under the action of the drum. In such engines, &c., as hitherto constructed the periphery of the drum and the inner cylindrical surface of the casing or cylinder have the same speed; but in consequence of the eccentricity and the fact that the end walls of the cylinder are fixed to the cylinder, and consequently have to make the same number of revolutions as the latter, the said end walls will have a speed different from that of the end surfaces of the piston. The said difference in the speeds of the end surfaces of the drum and the end walls of the cylinder is comparatively greater near the center of the drum and decreases toward its periphery. There is also at the said periphery a difference in the speeds of the drum ends and the said end walls, and between the speed of the ends of the pistons rotating in contact with the end walls and the speed of the said walls there is a difference which is greater. The greater portion of the piston extends beyond the periphery of the drum. The said differences in speed or the relative movement of the drum end and the ends of the pistons, on the one hand, and the end walls of the cylinder, on the other hand, are very disadvantageous to the durability of the engine as well as to the tightness between the bearing-surfaces of the parts, as the said surfaces must fit air-tight, the sliding pistons and the slots provided for the same in the drum making the arrangement of suitable

tightening means in the ends of the drum impossible. Nor in the end walls of the cylinder in machines constructed as stated above tightening means—as, for instance, tightening-rings—can be provided, as such means, owing to the eccentricity of the drum and the end walls of the cylinder, would have a position eccentric to the drum, and consequently would be of very little or no use. For the said reasons the engines must be so arranged that the ends of the drum and the pistons fit as good as air-tight between the end walls of the cylinder, as mentioned above, in order that not too great a quantity of motive fluid may leave the engine between the bearing-surfaces of the said parts. The said arrangement may certainly be made without causing too great a friction, as the end walls of the cylinder partake in the rotation; but at the slightest variations in the temperature the drum and its pistons usually will have a higher temperature than the cylinder, which results in the drum and the pistons being locked between the said end walls or their running with such a great friction against the said walls that a great part of the force is lost in spite of the mutual rotating movement of the parts, which is normally also the case, but in smaller extent, if the said bearing-surfaces fit sufficiently close not to permit leakage. It has even happened that the sliding pistons in machines of the construction stated above have been so firmly locked between the end walls of the cylinder that they have been broken.

This invention has for its chief object to remove the said disadvantages, which is gained by arranging the casing or cylinder of the engine, &c., as a ring free from the end walls and caused to partake in the rotation of the drum only by the friction against the same and the end walls, which are fixed to or made integral with the drum, as clearly stated below with reference to the accompanying drawings, in which—

Figure 1 is a transverse vertical section view of an engine arranged in accordance with our invention, and Fig. 2 is a longitudinal vertical sectional view of the same engine.

In the said figures, 1 is the frame of the en-

gine. 2 is the shaft journaled in roller-bearings 3, arranged in the end pieces or covers 4 of the said frame. The shaft 2 has a longitudinal bore 5, in which is loosely mounted 5 a pipe 6, fixed to the frame and communicating with the inlet-pipe 7 for the motive fluid. 8 is the piston-drum of the engine, fixed on the shaft 2 or made integral with the same. The said piston has a channel 9, communicating 10 with a port 10 in the shaft 2. Also in the pipe 6 a port 11 is provided, said ports 10 and 11 being so located that they correspond once during one revolution of the shaft and the drum, thus permitting motive fluid to pass 15 into the engine to exert its force against the right-hand side of the piston 12, Fig. 1, sliding in a radial slot 13 in the drum, and so cause the drum and the shaft to rotate. During the rotation of the drum the said piston 20 is pressed by the centrifugal force against the inner wall of the casing or cylinder of the engine. According to our invention the said casing or cylinder consists of a ring 14, which is free from the end walls 15 15 of the casing, 25 Fig. 2. One of the said end walls is made integral with the piston 8 and the other wall is fixed to the same. The said ring 14 is supported by rollers 16 16, journaled on ball or roller bearings 17, and is caused to rotate 30 with the drum by the friction between the ring and the end walls 15 15 and the friction between the ring and the drum which bears upon the inner side of the ring, as shown in Fig. 1. The said ring 14 is made in two parts 35 to permit the mounting of a ring 18, of steel. After the said rings are placed on the drum they are held in position by the end walls 15 15, one of which is pressed against the drum and fixed to the same and the shaft 2 by means 40 of a nut 19, screwed on the shaft, Fig. 2. In the ends of the ring 14 recesses 20 are provided, in which packing-rings 21 of suitable material are mounted, pressed against the inner side of the end walls 15 15 by means of 45 springs 22 or the like, mounted in the said recesses, Fig. 2. In the inner sides of the end walls 15 15 grooves 23 are provided, Fig. 2, serving as guideways for the ends of the pistons 12. In Fig. 2 a portion of the piston 50 12 is broken away in order that one of the said grooves 23 may be visible. 24 is an ejection-port for the exhaust fluid. As easily understood from the above, motive fluid is admitted in the right chamber 25 55 of the engine each time the port 10 coincides with the port 11 of the pipe 6, which fluid presses against the piston 12 until the latter has reached the contact-point between the drum and the cylinder and the ejection-port 60 24 has passed by the said point. The drum 8 will then continue in its rotation, owing to the inertia of the parts, and motive fluid is thereupon again admitted in the chamber 25, and so on. By the said provision of grooves 65 23, which is possible through the connection

of the end walls with the drum, the piston is suitably supported when projecting from the drum, thus being not liable to be broken off when acted upon by the fluid-pressure at the right-hand side, Fig. 1.

According to our invention the piston is composed by two or more plates, Fig. 1, free from each other and mounted at the side of each other, each bearing against the inner side of the ring 14 and tightening against the same. 70 By the said arrangement of the piston its outer edge will adjust itself transversely to the inner side of the ring at every position of the piston, and thus fit closely to the ring. 75

As seen from the above, there is not relative movement between the drum with its piston and the end walls of the cylinder, said relative movement or difference in motion existing now at the bearing-surfaces of the ring and the end walls connected with the drum. At 80 the said bearing-surfaces suitable tightening means—as, for instance, tightening-rings, as shown in the drawings—can easily be provided, the close fitting of the surfaces moving in relation to each other, which is necessary 85 in the engines as hitherto constructed, being thus not necessary in engines arranged in accordance with our invention. Thus the greatest part of the friction between the surfaces movable to each other in engines of the old 90 construction will obviously be removed by our invention, as the bearing-surfaces in our engines are yielding. At the same time the difference in the speeds of the said surfaces is 95 reduced, owing to the fact that the relative movement now exists between parts situated nearer the periphery of the casing. 100

By our invention the construction of the whole engine will be considerably simplified, especially when composed of two or more cylinders with piston-drums—as, for instance, in compound or triple engines—in which case the piston-drum is provided with partition-walls in suitable distances from each other and arranged in such a manner that between each 110 two walls a cylinder-ring can be mounted, the engine being thus divided into working chambers which can be properly adapted to the different degrees of expansion. Owing to the fact that by the said arrangement each cylinder-ring can rotate independent of the other ring or rings, the said rings as well as the corresponding piston-drums may have different diameters, so that the length of the piston-stroke or the working chamber can be increased in proportion to the necessary augmentation of the volume of the successive working chambers. By this the essential advantage is gained that the proportion between the length, width, and depth of all working 115 chambers can be maintained, so that the volume necessary for each working chamber can be obtained with a minimum of area of the walls inclosing the said chamber, the conditions most suitable for the slightest possi- 120 125 130

ble cooling of the motive-fluid steam being thus created. The said arrangements of the working chambers would hardly be possible if the different chambers in a compound engine, for instance, be provided within a single cylinder by dividing the same into compartments by means of a partition-wall and by mounting two piston-drums on the shaft.

With regard to the practical execution the diameters of the two working chambers must be the same, in consequence whereof the difference between the volumes of the high-pressure chamber and the low-pressure chamber can be effected only by giving the said chambers different width longitudinally to the shaft.

In the drawings only one sliding piston is shown, but obviously two or more pistons may be employed. The motive fluid may consist of steam or other suitable elastic fluid. In applying our invention to internal-combustion engines the compression and working chambers may each be provided in the same easy manner as stated above with relation to compound and similar engines. In both cases the advantage is gained that each cylinder-ring rotates between its corresponding end walls independent of the adjacent ones, in consequence whereof it may be guided in a position most suitable for an easy running and the slightest possible wear of the parts—*i. e.*, without being subjected to any unfavorable pressure from or acted upon by the end walls. Our invention may obviously be applied to pumps and similar apparatus. In the practical execution of our invention the arrangements shown in the drawings may be modified in many respects without exceeding the limits of the invention defined in the claims.

Having now described our invention, what we claim as new, and desire to secure by Letters Patent, is—

1. In rotary engines, pumps and the like the combination of a rotating cylinder, con-

sisting of a ring which is free from the end walls of the cylinder, a piston-drum mounted eccentric in the said cylinder, and the end walls of the cylinder forming end pieces on the said drum and fitting against the ends of the said ring, substantially as described and for the purpose set forth.

2. In rotary engines, pumps and the like the combination of a rotating cylinder, consisting of a ring which is free from the end walls of the cylinder, a piston-drum mounted eccentric in the said cylinder, the end walls of the cylinder forming end pieces on the said drum and fitting against the ends of the said ring, one or more tightening-rings in the end surfaces of the cylinder-ring and means for pressing said tightening-rings against the end walls of the cylinder, substantially as described and for the purpose set forth.

3. In rotary engines, pumps and the like the combination of a rotating cylinder, consisting of a ring which is free from the end walls of the cylinder, a piston-drum mounted eccentric in the said cylinder, the end walls of the cylinder forming end pieces on the said drum and fitting against the ends of the said ring, one or more tightening-rings in the end surfaces of the cylinder-ring, the sliding piston or pistons of the drum, said pistons consisting of plates independent of each other and mounted at the side of each other, and grooves provided in the said end pieces of the drum and guiding the said piston or pistons, substantially as described and for the purpose set forth.

In witness whereof we have hereunto signed our names, this 6th day of September, 1904, in the presence of two subscribing witnesses.
